UNITED STATES PATENT OFFICE.

JOHN PRUTSCHER, OF CHICAGO, ILLINOIS.

WIREWORKING APPARATUS.

Application filed November 15, 1921. Serial No. 515,293. Renewed February 16, 1924.

To all whom it may concern:

Be it known that I, JOHN PRUTSCHER, a citizen of the United States, residing at Chicago, in the county of Cook and State 5 of Illinois, have invented new and useful Improvements in Wireworking Apparatus, of which the following is a specification.

This invention which is the subject matter 10 of the present application for patent has been designed for bending wire in a manner to produce an open-work fabric of ornamental design, suitable for use in connection with flower baskets and other structures.

The invention has for its object to provide 15 a wire-bending machine or apparatus embodying certain novel and improved features of construction and modes of operation to be described in detail hereinafter, and in order that the same may be better understood, reference is had to the accompanying drawings, forming a part of this specification.

In the drawings:

Figure 1 is a plan view of the machine; 25 Fig. 2 is an end view thereof; Fig. 3 is a cross-section on the line 3-3 of Fig. 1; Fig. 4 is a front elevation, and Fig. 5 is a longitudinal section on the line 5-5 of Fig. 1.

The invention contemplates the employment 30 of a series of formers so shaped and arranged that when the wire, shown at W in Fig. 1, is bent around the same, there is produced an open-work fabric of ornamental design. Several rows of formers are employed as shown at 10, 11, 12, 13, 14 and 35 15, respectively, in Fig. 1, the rows being parallel and extending in the direction of the length of the machine. The formers 10 are secured by suitable fasteners 10^a to the top of a longitudinal base plate 10^b, the formers 11 are secured by fasteners 11^a to a base plate 11^b. Formers 12 are secured by fasteners 12^a to a base plate 12^b. Formers 13 are secured by fasteners 13^a to a base plate 13^b. Formers 14 are upstanding pins carried by a longitudinal base plate 14^a and passing loosely through a stripper plate 14^b positioned above the latter. The formers 15 are secured by fasteners 15^a to a base plate 15^b. The plates 10^b, 11^b, and 12^b are stationary and so supported by the ends 40 16 of the supporting frame of the machine. The plates 13^b, 14^a and 15^b are supported 45 by the supporting frame ends for a vertical movement. The supporting frame includes

a base 17 from which the end walls 16 rise, the latter walls, at one end of the machine carrying bearings 18 for a transverse stationary shaft 19. On top of the walls 16 is mounted a plate 16^a.

The base plates 11^b and 12^b are spaced from each other, and in the space is located a work-elevating device in the form of a lifting bar 20 which has pivotally connected 60 to one end, as shown at 21, a link 22. On shaft 19 is fulcrumed an angle lever 23 having one of its arms connected to the link, as shown at 24, the arrangement being such that the bar 20 is moved in the 65 direction of its length when the angle lever is operated. The bottom edge of the bar 20 has a notch 25, one end of which is inclined, as shown at 26. This notch, as shown in Fig. 5, is adapted to seat over a 70 raised portion at the top of a post 27 rising from the base 17 and covered with a wear plate having an incline 28 on which the incline 26 seats. The forward end of link 75 22 also has a notch 29 provided with an 80 incline to seat on an inclined portion 30 of a plate carried by the adjacent end wall 16. The inclines are so located that a rearward movement of the link 22 and the bar 20 also causes said parts to rise as shown 85 by dotted lines in Fig. 5, whereas a movement in the opposite direction causes the same to lower to the position shown in full lines in Fig. 5, this being the normal position of the link and the bar. 90

Beneath the base plate 15^b is located a series of cams 31 for elevating the same. Any suitable number of cams, according to the length of the plate, will be provided. Each cam is mounted on a stationary transverse shaft 32. The entire set of cams is joined for simultaneous operation by a connecting bar 33. On shaft 19 is fulcrumed an angle lever 34 connected by a link 35 to the bar 32. Fig. 4 shows the cams 31 in 100 position for holding the plate 15^b elevated, and upon swinging the angle-lever 34 in the proper direction, the cams are tilted away from the bottom of said plate, as shown dotted in Fig. 4, whereupon the plate 105 is lowered by means of springs connected to the bottom thereof and anchored to the base 17. One of these springs is shown at 36 in Fig. 4.

A raising and lowering means for the 110 plates 13^b and 14^a, in all respects similar to the one just described, is also provided.

One of the lifting cams of plate 13^b is shown at 37 and its operating lever at 38, and one of the lifting cams of plate 14^a is shown at 39 and its operating lever at 40. The 5 cams 37 and 39 are fulcrumed on shaft 32, and the levers 38 and 40 are fulcrumed on shaft 19.

When the machine is adjusted for operation, the several rows of formers are all 10 positioned at the same level so that the wire W may be bent around the same. At the completion of the bending operation the work is removed from the machine, which is done in the following manner:

15 The hand-lever 34 is operated to lower the formers 15 around which the wire is looped. However the work does not drop it being held up by a longitudinal edge strip 41 extending along the front of the machine. The loops formed in the wire by the formers 15 are now closed up by twisting the wire together adjacent to the pins 14 as shown at w in Fig. 1. The hand levers 40 and 38 are now operated to lower 20 the pins 14 and the formers 13. The work now remains on the formers 10, 11 and 12, and upon operating the hand lever 21 it is pushed upwardly off the same.

I claim:

30 1. In a wire-bending machine, a plurality of formers arranged in rows, certain of said rows being spaced, and work elevating means in the space between said rows for stripping the work off the formers.

35 2. In a wire-bending machine, a plurality of formers arranged in rows, certain of said rows being spaced, work elevating bars in the space between said rows for stripping

the work off the formers, said bars having 40 bottom inclines, supports for the bars having inclines on which the bar inclines seat, and means for moving the bars in the direction of their length.

3. In a wire-bending machine, a plurality of formers arranged in rows, base plates 45 carrying the formers, certain of said base plates being vertically movable, means for holding the last-mentioned plates elevated, and means for lowering said plates to remove the formers thereof from the work.

4. In a wire-bending machine, a plurality of formers arranged in rows, base plates carrying the formers, certain of said base plates being vertically movable, cams engageable with the bottom of the last-mentioned plates for holding the same elevated, means for operating the cams to permit said plates to lower to remove the formers thereof from the work, and means for lowering said plates when the cams are so operated.

5. In a wire-bending machine, a plurality of formers arranged in rows, base plates carrying the formers, certain of said base plates being spaced and others being vertically movable, means for holding the last-mentioned plates elevated, means for lowering said plates to remove the formers thereof from the work, and work elevating means in the space between the spaced bars for stripping the work off the formers of said bars.

In testimony whereof I affix my signature.

JOHN PRUTSCHER.
